(57) **CLAIM**

We claim the ornamental design for a power supply enclosure, as shown and described.

DESCRIPTION

FIG. 1 is a top view of a power supply enclosure;
FIG. 2 is a bottom view thereof;
FIG. 3 is a front/left/top perspective view thereof;
FIG. 4 is a front/right/top perspective view thereof;
FIG. 5 is a front/right/bottom perspective view thereof;
FIG. 6 is a front/left/bottom perspective view thereof;
FIG. 7 is a left side view thereof;
FIG. 8 is a right side view thereof;
FIG. 9 is a front view thereof;
FIG. 10 is a rear view thereof;
FIGS. 11-18 show the power supply enclosure of FIGS. 1-10 with the cover in an open position.
FIG. 11 is a left side view of the power supply enclosure with the cover in the open position;
FIG. 12 is a right side view thereof;
FIG. 13 is a bottom view thereof;
FIG. 14 is a top view thereof;
FIG. 15 is a front view thereof;
FIG. 16 is a rear view thereof;
FIG. 17 is a front/right/bottom perspective view thereof; and,
FIG. 18 is a front/right/top perspective view thereof.
The broken lines shown represent unclaimed subject matter and form no part of the claimed design. The electrical plug is shown with a symbolic break in its length. The appearance of any portion of the article between the breaks forms no part of the claimed design.

1 Claim, 12 Drawing Sheets
